UNITED STATES PATENT OFFICE.

ELWOOD S. WHITE, OF GLEN COVE, NEW YORK.

GAS-BURNER INDICATOR AND CONTROL.

Application filed October 20, 1921. Serial No. 509,072.

To all whom it may concern:

Be it known that I, ELWOOD S. WHITE, a citizen of the United States, and a resident of Glen Cove, county of Nassau, and State of New York, have invented a certain new and useful Gas-Burner Indicator and Control, of which the following is a specification.

The invention relates to a device by means of which a valve may be manipulated from a distant point whereby the gas in a water heater, or the like, may be turned on or off from the distant point, and more particularly to use in connection with a gas burner provided with a pilot light, by means of which the gas issuing from the burner will be ignited when the valve is so turned as to permit of the escape of gas through the burner.

The objects of the invention are to provide an apparatus of the character described by means of which the gas may be turned on from a distant point; by means of which mechanism at the distant point will indicate whether or not the devices at the burner are in proper condition to be lighted; and by means of which the gas cannot be turned on unless the pilot flame is burning.

These and further objects will more fully appear in the following specification and accompanying drawings considered together or separately.

One embodiment of the invention is illustrated in the accompanying drawings, in which like parts in each of the several figures are designated by similar characters of references, and in which

Fig. 1 is a diagrammatic view of an apparatus embodying the invention.

Fig. 2 is a similar view of a modification.

Fig. 3 is a diagrammatic view of another modification.

Fig. 4 is a similar view of a further modification, and

Fig. 5 is a similar view of a still further modification.

In the drawings 1 designates a burner carried on and in communication with a gas pipe 2 in which is located a valve 3. On the stem of the valve is secured a double lever 4. A pivoted armature 5 engages with its free end the lever at one side of the stem,

and a pivoted armature 6 engages with its free end the lever at the opposite side of the stem whereby as one or the other of the 55 armatures is energized, the lever will be pivoted and the valve will be opened or closed as the case may be.

Cooperating with the armature 5 is an electromagnet 7 in a circuit 8 which includes 60 a source of electrical energy, such as a battery 9, a push button 10, and a magnet 11.

Cooperating with the armature 6 is an electromagnet 12 in a circuit 13 which includes the battery 9, a push button 14, a 65 magnet 15 and a thermostatic contact element 16. The element 16 comprises an arm 17 carrying a contact, and an arm 18 formed of two different metal strips arranged side by side and in contact with each other and carrying a contact point. The arms 17 and 18 are carried on an insulating base, and the free end of the arm 18 extends over the burner 1 and over the end of a pilot tube 19 communicating with the pipe 2, with the 70 valve 3 between the point of communication and the burner 1 whereby the pilot light will burn when the valve is closed.

A single armature 20 cooperates with the magnets 11 and 15 and will, by its position indicate whether the valve 3 is open or closed.

The push buttons 10 and 14, and the magnets 11, 15 and their armature 20 are preferably situated in a station 21 located at 85 a distance from the burner 1 and the device to be heated thereby. Instead of, or in addition to, the indicator above described, the station 21 may comprise a buzzer in either of the circuits 8 or 13, preferably the latter, 90 whereby an auditory signal may be given.

The burner being part of a water heater located in a bathroom, the station 21 may be conveniently located in a bedroom, or there may, if desired, be a plurality of stations 95 located at different places and all electrically connected to the same heater. Or there may, if desired be a plurality of heaters operated from a common station.

In the embodiment of the invention illustrated in Fig. 2, a luminous signal such as a lamp 22 in an independent circuit 23 may be employed. In the circuit 23 is located a pair of spaced spring arms 24 and 25 nor-

mally spaced apart and which may be brought into contact by means of a pin 26 on the lever 4 when the valve 3 is in open position. In the circuit 8^a the push button 10 is positioned, and the push button 14 is in the circuit 13^a which includes the element 16.

The operation of the form of device illustrated in Fig. 1 is as follows:

10 The pilot light burning as it will because of the connection of its tube with the gas main 2 below the valve 3 will keep the thermostatic element 18 hot, and said element will be in position to close the contact with 15 the arm 17 and circuit 13, or 13^a as the case may be will be closed.

When it is desired to light the burner the circuit will be closed by pushing the button 14, the circuit will then be from the battery 9 through the magnet 15, which will attract the armature 20 and move the same to indicate "On" and operate the buzzer. The current will pass through the closed contact 17—18 energize the magnet 12 which 25 will attract its armature 16 and the latter will engage the lever 4 and open the valve 3. The gas escaping from the burner will be ignited by the pilot flame.

If, when the valve is turned off, the pilot 30 flame should be accidentally extinguished, the thermostatic member will contract because of the absence of heat, and the contact 17—18 will be broken. If, now, the button 14 be pressed none of the magnets will 35 be energized and the armature 20 will indicate "Off," and the valve 3 will remain closed. There will be no escape of gas from the burner, and danger from that source will be avoided.

40 The operator will know from the fact that there has been no response at the station 21, that the pilot light has been extinguished, and it will be necessary for him to relight it before he can operate the station to light the burner. The operator will 45 know that the gas has been escaping from the tube 19 and he will, when he enters the bath-room, act accordingly, and danger from an explosion, or asphyxiation will be 50 avoided.

When it is desired to extinguish the flame at the burner, the button 10 is pressed, the magnets 7 and 14 are energized and the lever 4 is moved to close the valve, and the armature 20 will indicate the fact that the gas 55 has been turned off.

In the modification illustrated in Fig. 2 the operation is the same as that above described, except that when the lever is moved 60 to open the valve the pin 26 will make a contact at 24—25 in a lighting circuit and a lamp 22 will be lighted. When the valve is closed the contact 24—25 will be broken and the lamp extinguished.

65 In Fig. 3 is shown an arrangement in

which a single burner may be operated from a plurality of stations such as that shown at 21 in Fig. 1.

Fig. 4 shows a wiring arrangement in which two stations such as 21^a may be employed in connection with a single burner.

Fig. 5 shows diagrammatically a wiring arrangement in which a plurality of burners may be operated from one or more stations such as shown at 21^a, or by eliminating the 75 circuit 23 the burners may be operated from one or more stations 21.

While the invention has been described in connection with a water heater, it is to be understood that the same may be carried 80 out in connection with other forms of devices such as gas stoves, gas logs, (so-called) etc.

In accordance with the provisions of the patent statutes the principle of the invention has been described, together with the apparatus which is now considered to represent the best embodiment thereof, but it is desired to have it understood that the apparatus shown is merely illustrative, and 85 that the invention may be carried out in other ways.

The invention having been described what is claimed as new and desired to be secured by Letters Patent, is as follows:

95 1. A device of the character described, comprising a gas supply pipe, a burner on the pipe, a pilot light tube in communication with the pipe and having an opening in proximity to and above the burner, a valve in the pipe between the pilot tube and the burner, an electric circuit including a magnet for moving the valve to open position, said circuit being interrupted by a break therein, a thermostatic element acted 100 on by the flame of the pilot tube to close the break in the circuit, a switch in the circuit, and means governed by the position of said switch for indicating whether or not said pilot tube is lighted, and a switch for closing the valve, said switches and indicating means being located at a distance from the burner.

110 2. A device of the character described, comprising a gas supply pipe, a burner on the pipe, a pilot light tube communicating with the pipe, said tube having an opening in proximity to and above the burner whereby a flame on the tube will ignite gas escaping from the burner, a valve in the pipe 115 between the tube and burner, a magnet for moving the valve to closed position, an electric circuit in which the magnet is located, a signal magnet in the circuit, a push button in said circuit, a second electric circuit, 120 a magnet located in said second circuit adapted to open the valve, a second signal magnet in the second circuit, a second push button being in said second circuit, an armature common to both signal magnets, there 125

being an interruption in the second circuit, and responsive means acted on by the flame of the pilot tube to close said second circuit when the pilot tube is lighted and to break said circuit when the tube is unlighted whereby said second push button will be inoperative.

This specification signed and witnessed this 14th day of October, 1921.
